CARBON BRUSH

Maurice Guarner, Schenectady, N.Y., assignor to General Electric Company, a corporation of New York

Application September 30, 1957, Serial No. 687,137

4 Claims. (Cl. 310—249)

The invention described herein relates to carbon brushes of the type used in dynamoelectric machines and more particularly to an improved combination of shunt and brush adapted for use in atmospheres highly corrosive of bare copper conductors.

Conventional carbon brush structure consists of a copper shunt riveted or otherwise secured to a carbon body for conducting current to or from the commutator of a dynamoelectric machine. It is well known that when a machine having such a brush is operated in an atmosphere containing elements corrosive of the copper parts used in the brush, rapid corrosion of the shunt wire takes place, thus destroying the brush before the useful life of the carbon has been realized. The adverse effects are particularly noticeable in steel mill and paper mill applications where the air is highly laden with sulphur and chlorine fumes and in order to eliminate the corrosive action on the copper parts including the shunt, attempt has been made to coat the shunt with substances resistant to attack by the corrosive ingredients.

The use of wire enamel has been suggested, but the primary disadvantage is that the enamel must be removed from areas of the shunt to permit soldering of terminals and to secure firm electrical contact with rivets utilized in securing the shunt to the carbon body of the brush. The degree of enamel removal cannot be closely controlled so that an excessive amount of bare wire is presented for attack by the chemical constituents. The applications found to be most successful are those wherein the carbon shunt is coated with a metal, such as lead or cadmium, for example, but these substances also are attacked by the corrosive elements in much the same manner as the copper but to a lesser degree.

The primary object of my invention therefore is to provide a carbon brush having a shunt coated with a resin for protecting the copper therebeneath from attack by air-borne chemicals prevailing in industrial areas.

In carrying out my invention, I coat the individual wires comprising the brush shunt with a resin capable of protecting the copper wire therebeneath from air-laden chemicals not compatible with the copper, prior to attaching a small copper sleeve on the shunt at a point equidistant the shunt ends. The shunt or wire with the sleeve fixed thereon is welded to a metallic clip adapted for connection to the carbon body of the brush by means of rivets or other well known securing means. In a modification, the resin coated shunt is susceptible of attachment directly to rivets incorporated in the carbon body. Heat is then applied to the brush for melting the resin on the shunt at its point of attachment so as to achieve proper electrical connection between the parts.

The subject matter which I regard as my invention is particularly pointed out and distinctly claimed in the concluding portion of this specification. My invention, however, both as to organization and method of operation, together with further objects and advantages thereof, may best be understood by reference to the following descrip-

2

tion taken in connection with the accompanying drawings in which:

Figure 1 is a perspective view of a carbon brush including a carbon body and a shunt attached thereto by means of a clip installed on a central part of the brush;

Figure 2 is a view illustrating a copper shunt with a small copper sleeve fixed thereon equidistant the shunt ends;

Figure 3 illustrates the arrangement of parts after the shunt of Figure 2 is welded to a clip;

Figure 4 is a view in elevation, partly in section, showing the arrangement of a rivet utilized for securing the clip to the carbon body;

Figure 5 is a view in elevation illustrating a modification of the brush shown in Figures 1 through 4; and

Figure 6 is a view in elevation, partly in section, of the brush shown in Figure 5.

Referring now to the drawings wherein like reference characters designate like or corresponding parts throughout the several views, there is shown a carbon brush consisting of a carbon body 10 having a clip 12 secured thereto by means of a rivet 14 extending transversely through the carbon body. A coated copper shunt 16 having a terminal 18 connected to the ends thereof, is provided with a copper sleeve 20 which serves to facilitate the welding of the copper shunt 16 to clip 12 at the point indicated at 22.

Many different types and variations of resin coatings are adapted for application to the carbon shunt 16 and one example found to be extremely successful in practicing the invention disclosed herein is disclosed in the co-pending patent application of D. W. Fox and A. F. Zavist, Serial No. 588,557, filed May 31, 1956, and assigned to the same assignee as the present invention. The invention of the Fox et al. application provides for a polyester resin base composition which can conveniently be removed to permit soldering, but which has the desirable physical characteristics of the polyester resin base material and, in particular, its heat stability. More specifically, the invention of the application comprises the method and the material resulting from the admixture of (1) a composition consisting essentially of the reaction product of (a) from about 25 to 56 equivalent percent of a lower dialkyl ester of a member selected from the class consisting of isophthalic acid and terephthalic acid and mixtures of such members, (b) from about 15 to 46 equivalent percent of ethylene glycol, and (c) from 13 to 44 equivalent percent of a saturated aliphatic polyhydric alcohol having at least three hydroxyl groups and (2) a polyurethane or polyisocyanate.

Another type of resinous coating found to be satisfactory consists of a polyvinylal resin, blended in solution with a diisocyanate to produce a polyurethane film.

The polyvinylal resins are produced by suitably combining an aldehyde with a partially or completely hydrolyzed polymerized vinyl ester. Among the aldehydes which may be used to make the polyvinylal resins are formaldehyde, acetaldehyde, propionaldehyde, butyraldehyde, benzaldehyde, etc. Among the polyvinyl esters one may use to make the polyvinylal resins are, for instance, polyvinyl acetate, polyvinyl propionate, polyvinyl butyrate, etc. The properties of the polyvinylal resins may be varied through a wide range by varying the viscosity and the extent of the hydrolysis of the polyvinyl during hydrolysis. Methods for preparing these polyvinylal resins are more particularly described in Reissue Patent 20,430—Morrison et al., as well as Jackson and Hall patent, 2,307,588, assigned to the same assignee as the present invention, which by reference are made part of the disclosures of the present application. Application of the polyurethane film to the individual wires of the copper conductor produces a product capable of being bent

and twisted without creating cracks or other openings in the film through which the corrosive elements would otherwise penetrate and attack the copper. This latter material has been found particularly effective in resisting attack by chlorine and sulphur fumes prevalent in steel mill and paper mill areas and it will be evident that other equivalent resinous materials may be resorted to for protecting the shunt wire.

Operation

In operation, stranded conductor wire coated with a polyurethane film or resin of the type described above, for example, is cut to a predetermined length sufficient to permit convenient attachment of the brush and wire to a source of voltage supply. The thin copper sleeve 20 is loosely fitted on the stranded wire conductor at a point equidistant its ends. The wire with its sleeve 20 is then placed in the clip 12 and welded thereto by a machine capable of providing pressure to squeeze the sleeve and wire tightly together while simultaneously passing sufficient current through the sleeve, wire and clip to obtain a firm welding connection between these parts. During the welding operation, heat generated as a result of resistance to flow of electric current, is sufficient to melt and volatilize the resin from the stranded conductor at those points immediately underlying the copper sleeve placed on the stranded wire, while also carrying out a welding function. Such heat is necessary to break down the insulating qualities of the resin and thereby obtain a clean electrical connection between the copper wire and the copper sleeve. The clip 12 with its welded wire conductor is then attached to the carbon body 10 by means of the rivets 14.

As is evident, the resin on the ends of the wire adapted for receiving the terminal 18 also must be removed in order to obtain complete electrical connection between the parts. This is accomplished by inserting the ends of the conductor wire into the terminal and then applying a large pressure to tightly clamp the terminal around the free ends of the coated wire and thereby achieve a firm mechanical connection therebetween. Removal of resin from the wire to permit transfer of electric current to the terminal is accomplished by dipping in a bath of molten solder. The heat thus transmitted through the terminal to the coated wire melts and volatilizes the resin and exposes the bare copper wire to the inner portions of the terminal. The wire and its attachments thus constitute the brush shunt.

In lieu of using a solder bath, other heat sources may be utilized, such as the use of sand heated to a high temperature, a salt solution, or a gas flame, for example, issuing from an acetylene torch. It will be noted that the primary purpose of the heat is to destroy the resin on the wire located within the terminal and any type of heat source may be resorted to that will effectively carry out a heat transferring function.

The same principles are applicable to the embodiment shown in Figures 5 and 6, but instead of using the clip 12, the shunt 16 is wrapped directly around rivets 14. As the rivets are spun, the copper shunt is rigidly affixed to the carbon body 10, thereby providing a firm mechanical connection therebetween. In order to effect removal of resin from the wire and thereby establish electrical connection between the brush and wire, the brush is immersed in a bath of hot material, such as solder, having a temperature sufficient to melt and volatilize the resin. Immersion is made only to a point where heat can be transmitted to the rivet to accomplish removal of the resin on those portions of shunt in engagement with the rivets. The solder will not adhere to the carbon brush so that upon its removal from the bath, no metallic parts will remain on the brush which would

thereafter serve to damage the commutator or adversely effect operation of the machine.

It will be evident that many modifications and variations are possible in light of the above teachings. The inventive concept embodied herein is that of providing a combined carbon body and copper shunt coated with a resin resistant to the attack of chemicals in the atmosphere in industrial areas. The process employed for establishing electrical connection between the conducting parts is also unique in that removal of the resin need not be made until the parts are mechanically secured together.

What I claim as new and desire to secure by Letters Patent of the United States is:

15 1. In combination, a carbon brush adapted for use in corrosive atmospheres comprising a carbon body having a clip secured to the one end thereof, a shunt comprising a plurality of copper wires individually coated with a polyurethane resin and assembled to form a single conductor, a copper sleeve on said shunt equidistant its ends, welding means securing said sleeve and therefore said shunt to said clip so as to secure said shunt in intimate electrical and mechanical contact with said clip, and thereby provide a carbon brush resistant to the corrosive effects of air-laden chemicals.

20 2. The method of assembling a carbon brush comprising the steps of coating the individual wires of a stranded conductor with a polyurethane resin, loosely mounting a copper sleeve on said conductor intermediate its ends, 25 placing said conductor with its attached copper sleeve in a brush clip and applying pressure and heat to said copper sleeve and clip for compressing said sleeve into intimate contact with said conductor while simultaneously welding said sleeve with its enclosed conductor to said clip whereby the heat imparted to said sleeve and wire is of sufficient value to melt and volatilize the resin on said conductor and thus obtain electrical contact between said sleeve and said conductor, and mounting said clip with its attached conductor to said brush.

30 3. The method according to claim 2 including the additional steps of inserting the free ends of said resin coated conductor into an opening provided in a terminal, compressing the ends of said terminal in rigid mechanical relationship with the ends of said conductor, and immersing said terminal in a heated medium having a temperature sufficient to melt and volatilize the resin on said wire so that when heat is transmitted through said terminal clip, the resin is removed, thereby providing electrical contact between said conductor and said terminal.

35 4. The method of assembling a carbon brush comprising the steps of coating the individual wires of a conductor with a polyurethane resin and assembling said wires into a stranded conductor, looping a portion of said conductor equidistant its ends over a rivet provided in an outer end of a carbon brush body, spinning said rivets to rigidly affix said conductor into firm mechanical relationship with said carbon body, immersing a portion of said carbon body up to the rivets in a heated bath 40 of solder having a temperature sufficient to melt and volatilize the resin between said rivets and conductor so as to achieve proper electrical connection between said brush and said conductor.
